UNITED STATES PATENT OFFICE.

PERCY Q. WILLIAMS, OF CINCINNATI, OHIO.

APPARATUS FOR RECEIVING GLASSWARE.

Application filed June 3, 1922. Serial No. 565,732.

To all whom it may concern:

Be it known that I, PERCY Q. WILLIAMS, a citizen of the United States of America, and a resident of Cincinnati, in the county 5 of Hamilton and State of Ohio, have invented a new and useful Improvement in an Apparatus for Receiving Glassware, of which the following is a specification.

My invention relates to apparatus for receiving glass ware such as bottles, jars, etc., and transferring them to a leer and placing them in position on the leer conveyor, and is 10 in the nature of a device disclosed by me in my co-pending application Serial #516,518, filed Nov. 21, 1921. This device disclosed 15 herein is for use in handling small bottles.

An object of my invention is to simplify the conveyor mechanism.

Another object of my invention is to provide 20 a device that will be more simple in operation than are the devices which up to this time have been used for this sort of work.

Another object of my invention is to provide 25 a structure wherein all the operating parts are disposed without the leer, whereby the parts are protected against the wear and damage which necessarily accompanies the extension of operating parts and the subjection of the operating parts to the heat within the leer.

These and other objects are obtained by means described herein and disclosed in the accompanying drawings, in which:

35 Fig. 1 is a side elevation of a device embodying my invention.

Fig. 2 is a plan view of the device shown in Fig. 1.

40 Fig. 3 is an enlarged sectional view on line 3—3 of Fig. 1.

Fig. 4 is an end elevation of the parts shown in Fig. 3.

Fig. 5 is an enlarged sectional view on line 5—5 of Fig. 1.

45 Fig. 6 is an enlarged sectional view on line 6—6 of Fig. 2.

Fig. 7 is a diagrammatic view of the wiring forming a detail of my invention.

50 Fig. 8 is a fragmental perspective view of a leer conveyor plate forming a detail of my invention.

In devices embodying my invention, articles such as glass bottles are directed, by means of a chute 8, to an endless conveyor 9, which carries the articles to a leer 10, where the articles are annealed. As the

bottles are carried by the conveyor the bottles cool somewhat, but they are still sufficiently soft and pliable that if permitted to lie motionless upon the conveyor, the sides 60 of the bottles lose the form which is originally imparted to them. This is especially true in the bottles of the size and kind formerly referred to as beer bottles. As the bottles are carried by the conveyor 9, they 65 are rolled between the sides of the way or channel 84 thru which they are carried, thereby avoiding distortion of the bottles. The means whereby this is accomplished 70 consists of a series of air blasts which operate alternately upon the bottles from opposite sides of the way.

A main frame 11 for the conveyor belt 9 constituting part of the primary conveyor is pivoted at 12 upon a suitable support 13. 75 The support 13 is tubular and a draft of air may pass therethru. The pipes 14 of the blast system mounted on the frame 11 communicate with the tube support 13. The frame 11 comprises an upper track and a 80 lower track, each track consisting of bars 15 mounted on brackets 16, see Fig. 6, which brackets in turn are supported by angle irons 17 extending longitudinally of the frame, the angle irons of the upper and lower tracks being spaced by bars 18. Rollers 19 are revolvably mounted on axles 23 and are adapted to ride upon the bars 15. The axles 23 carry angle brackets 20. Rods 21 connect the angle brackets 20 disposed 85 on opposite sides of the track and carry a belt 22 preferably of asbestos. The rods 21 and the belt 22 are secured upon one another in any sort of a manner such as by being riveted upon one another. The rollers 19 are mounted upon the axles 23 carried by the angle brackets 20, and suitable fastening means such as cotter pins 24 secure the parts against separation and permit free 90 and ready movement of the belt. The links 25, 26, and 27 of the chain 28, which chain connects adjacent axles 23, may be readily 95 separated from any one of the axles 23 by removing the cotter pins from the axles carried by one of the rods 21, thereby permitting the entire structure of belt and rollers to be removed from the frame. The advantage 100 in making these elements removable is that the same leer may be used for various sizes and kinds of bottles, various types and kind of bottles however, requiring different types of primary conveyors in order to ex-

peditoriously and economically carry such various kinds of bottles to the leer. In order to carry out this object, the discharging end or auxiliary frame 29 may be detached from the main frame 11 whereby the sprocket wheel 30 and the chute 31 shown in Fig. 1 may be disassociated from the main frame and other auxiliary frames be mounted on the main frame. For this same reason 10 the guide 32 is removably mounted within the leer. The guide may be removably mounted in any suitable manner such as by bolting the ends of the guide upon the side walls 33 and 34 of the leer 10, as shown in Fig. 2. Another auxiliary frame of the nature to which reference has been made, is disclosed in my co-pending application filed of even date herewith, wherefore no further explanation of other auxiliary structures 20 need be given herein. The auxiliary frame 29 may be mounted upon the main frame in any suitable manner such as by means of brackets or plates 35, the ends of which are bolted upon the angle irons 17 and 119 of the body or main frame and the auxiliary frame respectively. Each chain 28 extends about sprockets 30 and 36. The sprockets 30 are carried by a shaft 37 mounted at the free end of the auxiliary frame 29, and 30 sprockets 36 are carried by the shaft 38 mounted adjacent the pivotally mounted or receiving end of the frame 11. The shaft 38 is adapted to be reciprocated longitudinally of the frame 11, in order to take up 35 any slack in the chain, and in order to accomplish this, a table 39 is slidably mounted at the receiving end of the frame, the table having arms 40 which extend downwardly on opposite sides of the frame, and support the shaft 38. A threaded lug 41 extends downwardly from the table 39, and is engaged by a screw 42 extending thru the end plate 420 of the frame, and carrying a suitable hand wheel 43 whereby the screw may be revolved. By referring to Fig. 1, and in view of the explanation, it is readily apparent that by revolving the hand wheel 43, the table may be reciprocated longitudinally of the frame. A motor 44 is mounted upon the 40 table 39, and is adapted to drive the shaft 38 by means of a suitable driving connection such as a chain 45 and the sprockets 46 and 47 carried by the motor and the shaft 38 respectively. The discharge end or rear 45 end of the frame 11 is supported by a structure disposed partly within a pit 48 formed below and intermediate the ends of the conveyor. A number of bars, such as the bars 18 which space the upper and lower tracks of the conveyor, and which are referred to as 49, extend below the lower track 50, and at their lower ends are secured upon a platform 51 carrying a motor 52, on the shaft of which motor is mounted a bevel gear 53. 50 A shaft 54 extends thru the platform 51 and carries at its upper end a beveled gear 55 which engages the bevel gear 53. The lower end of the shaft 54 carries a gear 56 which engages an arcuate rack 57. The rack 57 is supported by a channel bar 58 upon which 55 channel bar the rollers 59, carried by the brackets 60 extending from the platform 51, engage. The pit floor 61 carries a threaded bearing 62 which is engaged by a screw 63, on the lower end of which screw is mounted 60 either a hand wheel or a sprocket 64, and the upper end of which supports the channel 58. The upper end of the screw 63 has a globular head 640 which engages in a complementary socket formed in the block 65. The described structure is employed to raise and lower the rear or discharging end of the frame. It is desirable to provide a number of adjusting screws 63, the sprockets 64 carried thereby being connected by a suitable 65 chain 66, serving to secure even and equal adjustment of the ends of the channel. The ends of the channel bar may slidably engage suitable guide bars 120. Although the rear or discharge end of the frame may be elevated for proximately a foot, it has been found unnecessary in practice to provide any particular compensating structure at the front or pivotally mounted end of the frame. The movement of the frame at the receiving end, is very slight and the little strain resulting therefrom is of little consequence. It has been found in practice that by having an opening 67 in the floor 61 supporting the frame, of a size somewhat larger than the size of the pipe 69, the parts will function satisfactorily and efficiently. The pipe 69 is supported upon the foundation 61 by means of the ring 70 mounted on the pipe 69, the ring having an annular flange 71 which lies upon the floor and supports the pipe. The pipes 14 are mounted upon the pipe 69 in any suitable manner such as by means of a split ring 72 having radial flanges 73 which are bolted upon one another, see Fig. 5. The ring 72 has flanged slots 74 formed in it, the flanges 75 serving to position and retain the lower ends of the pipes 14. The pipes 14 communicate with air chambers 76 formed in casings 121 115 mounted on and extending longitudinally of the frame, and the air chambers communicate with a number of blast nozzles 77 disposed above and adapted to divert the air blast transversely to the belt 22 intermediate the belt and the side bars 82 and 83. Communication between the blast nozzles and the chambers 76 is effected by ports 78, and valves 79 are adapted to control the communication thru the ports 78. A number of blast nozzles 77 are disposed adjacently to one another throughout the length of the frame. A number of angular brackets 80 having elongated slots 81 are mounted upon the upper surface of the frame 11 and 120 125 130

support side bars 82 and 83 extending lengthwise of and above the belt 22. The brackets 80 may be adjusted so as to vary the width of the way 84 formed above the belt 22, such adjustment being made by means of bolts 85 mounted on the frames and extending thru the elongated slots 81 in the brackets 80. A nozzle 86 communicating with one of the pipes 14 is adapted 10 to direct part of the air blast lengthwise thru the way 84. By referring to Fig. 2 it is readily apparent that by closing certain of the ports 78 between their respective nozzles 77 and the chambers 76, it is possible 15 to secure air drafts in opposite directions at spaced intervals throughout the length of the way 84. This structure is of vital importance when the conveyor carries bottles such as are referred to as beer bottles. These 20 alternate air drafts serve to roll the bottles from side to side thereby precluding caving in or distorting of such bottles. The auxiliary frame 29 has mounted on it the angular plates 87 having a series of perforations 25 88 into which pins 89 mounted on arms 90 may enter. The arms 90 extend from the forward end of the chute 31, over which chute the bottles pass to the guide 32. A roller 91 is carried between the arms 90 and 30 is adapted to permit the free movement thereover of the bottles after they pass to the chute 31, and also permits any broken portions of bottles to be discharged from the primary conveyor without injuring the belt. 35 The roller 91 is adapted to engage the belt and to be frictionally and revolvably actuated thereby.

The means whereby the frame is oscillated, comprises the motor 52 which is electrically connected with a switch in the switch box 92 mounted on the platform 51. A shaft 93 extending from the switch box 92 carries an arm 94 at the lower end of which is a roller 95. This roller is adapted to be 40 brought into engagement with stops 96 and 97 disposed at opposite ends of the channel 58. The shaft 93 together with the arm 94 the roller 95, and the blocks 96 and 97 constitute a reversing mechanism whereby the motor 52 is reversed, thereby causing the frame to be oscillated. The rollers 59 supporting the platform 51 are mounted on 45 shafts 98. On each shaft 98 is mounted a bell crank lever 99 the lower end of which 50 carries a roller 100 adapted to engage cams 101 and 102 whereby the upper ends 103 of such levers effect an electrical connection between the contacts 104 and 105. The contacts 104 and 105 are embraced in an electrical circuit embracing a motor 106 adapted 55 to move or pull the leer conveyor 117. The shaft 107 which is driven from the motor 106 by means of gears 108 and 109, is connected with the leer in any suitable manner 60 to move the leer conveyor.

Referring to Fig. 7, 110 is the feed wire, 111 is a switch, and 112 is a rheostat adapted to control the speed at which the device operates. When the platform 51 reaches its left hand limit by virtue of the motor 52 being embraced in the circuit the current of which passes thru the wires 113, 114 thru the reversing switch 115, and to the motor thru the wire 116, the roller 100 engages the cam 102 and closes the circuit thru the contacts 104 and 105 disposed at the left hand side of the platform, the circuit thru said contacts 104 and 105 embracing the motor 106 and therefore causing the leer conveyor 117 to be moved. At about the time when the roller 100 engages the cam 102 the roller 95 engages the stop 96 thereby actuating the reversing switch so that the current passes to the motor 52 thru the wire 118, thereby reversing the direction of the motor and the direction of movement of the platform 52. As soon as the roller 100 is disengaged from the cam 102 the circuit thru the motor 106 is broken and the leer conveyor becomes stationary. When the platform 51 reaches its right hand limit, the same change in the direction of the motor is effected, and the leer is again temporarily actuated. 70

The leer conveyor comprises plates 122, carrying buffer strips 123, preferably of asbestos, and have their ends turned upwardly, whereby flanges 124 are formed, the flanges precluding engagement of the bottles on the side walls of the leer, and therefore avoiding crushing and marring of the bottles. The buffer strips preclude chipping of the glass when discharged into the leer. In Fig. 8, an angle bracket 125 is mounted on the end of the plate 122, instead of providing upwardly extending flanges on the ends of the 80 plates. 95

The operation of my device is as follows: Bottles pass to the belt 22 by way of the chute 8, the belt 22 being moved continuously by means of the motor 44. As the bottles 100 are carried thru the way 84 they are rolled back and forth between the sides of the way by means of the draft nozzles which discharge drafts of air from alternate sides of the way in a staggered relation. These air drafts serve both to cool the bottles and to roll the bottles so as to preclude caving in of the sides of the bottles. By the time the bottles have reached the last of the draft nozzles they have cooled sufficiently that they will hold their form, without further rolling, and the time necessary to carry the bottles from the last of the nozzles to the chute 31 allows the glass to set sufficiently that when they are brought into contact one with the other, they will not adhere. The bottles slide over the chute 31 onto the guide 32, and are piled up in a mass one on top of the other, the transverse movement of the conveyor serving to effect an even distribu- 110 115 120 125 130

tion over the leer conveyor 117. When the conveyor reaches either of its limits, the reversing switch and the leer conveyor are actuated thereby reversing the movement of the 5 bottle conveyor and actuating the leer conveyor. The air draft directed lengthwise of the way 84 by the nozzle 86 cooperates with the transverse air drafts in cooling the bottles. The discharge end of the frame may 10 be raised or lowered as may be necessary in view of the type of bottles to be carried into the leer. A suitable sliding door 126 is adapted to be moved laterally of the leer by the frame 11, and serves as a closure for the 15 forward end of the leer. An aperture of sufficient size is left in the door to permit the chute 31 to extend into the leer. When it is desired to use the conveyor and leer for other types of bottles requiring other means 20 of discharge from the bottle conveyor than those disclosed therein, the auxiliary frame is disconnected from the main frame, and the proper auxiliary frame is attached to the main frame 11. The tension on the 25 conveyor chains 28 and the conveyor belt 22 is varied by means of the hand wheel 43 whereby it is possible to loosen the chain sufficiently to remove the conveyor belt from the frame; and also take up any slack in 30 such chain and belt.

It should be observed that the belt 22 is disposed in alignment with the axes of the axles 24, whereby injury to the belt from carrying the belt about the sprockets at the 35 ends of the frame, is avoided.

What I claim is:—

1. In a device of the class described the combination with a pivotally mounted frame and an endless belt movable upon the 40 frame, of a mechanism to oscillate the frame about its pivotal mounting comprising a platform mounted on the frame, a bar over which the platform may move, an arcuate rack mounted on the bar, a motor mounted 45 on the platform, a shaft mounted on the platform having a driving connection with the motor, a gear carried by the shaft engaging the arcuate rack, and means to reverse the motor at the limits of oscillation 50 of the frame.

2. In a device of the class described the combination with a pivotally mounted frame and an endless belt movable upon the frame, of a mechanism to oscillate the frame about 55 its pivotal mounting comprising a platform mounted on the frame, a bar over which the platform may move, an arcuate rack mounted on the bar, a motor mounted on the platform, a shaft mounted on the platform having a driving connection with the motor, a gear carried by the shaft engaging the arcuate rack, means to reverse the motor at the limits of oscillation of the frame, and means to adjust the bar to vary the planes 60 within which the frame is oscillated.

3. In a device of the class described the combination of a floor, a pit formed in the floor, a leer at one end of the pit, a tube shaft extending thru the floor adjacent the pit, a bar vertically adjustable in the pit, a 70 platform laterally movable over the bar, an arcuate rack concentric with the tube shaft mounted on the bar, a shaft mounted on the platform, a gear on the shaft engaging the rack, a motor mounted on the platform adapted to revolubly actuate the shaft, a reversing switch for the motor and means to actuate the switch mounted on the bar and platform in such relation that the switch is actuated after a determinable relative 75 movement of the platform and the bar, a frame mounted on the platform, the frame being pivotally mounted at one end on the tube and having its other end disposed without and adjacent to the leer, an endless belt 80 mounted on the frame and a chute adapted to direct articles from the belt into the leer. 85

4. In a device of the class described the combination of a floor, a pit formed in the floor, a leer at one end of the pit, a tube 90 shaft extending thru the floor adjacent the pit, a bar vertically adjustable in the pit, a platform laterally movable over the bar, an arcuate rack concentric with the tube shaft mounted on the bar, a shaft mounted on the platform, a gear on the shaft engaging the rack, a motor mounted on the platform adapted to revolubly actuate the shaft, a reversing switch for the motor and means to actuate the switch mounted on the bar 95 and platform in such relation that the switch is actuated after a determinable relative movement of the platform and the bar, a frame mounted on the platform, the frame being pivotally mounted at one end on the tube and having its other end disposed without and adjacent to the leer, an endless belt 100 mounted on the frame, a chute adapted to direct articles from the belt into the leer, and a guide within the leer extending from 105 the chute to the floor of the leer.

5. In a device of the class described the combination of a floor, a pit formed in the floor, a leer at one end of the pit, a tube shaft extending thru the floor adjacent the pit, a bar vertically adjustable in the pit, a platform laterally movable over the bar, an arcuate rack concentric with the tube shaft mounted on the bar, a shaft mounted on the platform, a gear on the shaft engaging the rack, a motor mounted on the platform adapted to revolubly actuate the shaft, a reversing switch for the motor and means to actuate the switch mounted on the bar and platform in such relation that the switch is actuated after a determinable relative 110 movement of the platform and the bar, a frame mounted on the platform, the frame being pivotally mounted at one end on the tube and having its other end disposed with- 115

- out and adjacent to the leer, an endless belt mounted on the frame, a chute adapted to direct articles from the belt into the leer, a conveyor within the leer, means to actuate the leer conveyor, means adapted to intermittently actuate the leer conveyor actuating means, and a guide within the leer extending between the chute and the leer conveyor.
- 10 6. In a device of the class described the combination of a floor, a pit formed in the floor, a leer at one end of the pit, a tube shaft extending thru the floor adjacent the pit, a bar vertically adjustable in the pit, a platform laterally movable over the bar, an arcuate rack concentric with the tube shaft mounted on the bar, a shaft mounted on the platform, a gear on the shaft engaging the rack, a motor mounted on the platform adapted to revolubly actuate the shaft, a reversing switch for the motor and means to actuate the switch mounted on the bar and 75 platform in such relation that the switch is actuated after a determinable relative movement of the platform and the bar, a main frame mounted at one end upon the platform and having its other end pivotally mounted on the tube shaft, an auxiliary frame detachably mounted on the main 80 frame and extending adjacent to and being wholly disposed without the leer, a conveyor belt removably mounted on the main and auxiliary frames adapted to carry articles to the leer, a chute carried by the auxiliary frame extending into the leer and adapted to direct articles from the conveyor belt into the leer.
- 15 7. In a device of the class described the combination of a floor, a pit formed in the floor, a leer at one end of the pit, a tube shaft extending thru the floor adjacent the pit, a bar vertically adjustable in the pit, a platform laterally movable over the bar, an arcuate rack concentric with the tube shaft 85 mounted on the bar, a shaft mounted on the platform, a gear on the shaft engaging the rack, a motor mounted on the platform adapted to revolubly actuate the shaft, a reversing switch for the motor and means to actuate the switch mounted on the bar and platform in such relation that the switch is actuated after a determinable relative movement of the platform and the bar, a main frame mounted at one end upon the platform and having its other end pivotally mounted on the tube shaft, an auxiliary frame detachably mounted on the main 90 frame and extending adjacent to and being wholly disposed without the leer, a conveyor belt removably mounted on the main and auxiliary frames adapted to carry articles to the leer, a chute carried by the auxiliary frame extending into the leer and adapted to direct articles from the conveyor belt into the leer, a conveyor within the leer, a guide extending between the chute and the leer conveyor, means to actuate the leer conveyor and means controlling the leer conveyor actuating means adapted to intermittently render the leer conveyor actuating 95 means operative, whereby the leer conveyor may be actuated upon the arrival of the frame at its lateral limits of oscillation.
- 20 8. In a device of the class described the combination of a floor, a pit formed in the floor, a leer at one end of the pit, a tube shaft extending thru the floor adjacent the pit, a bar vertically adjustable in the pit, a platform laterally movable over the bar, an arcuate rack concentric with the tube shaft 100 mounted on the bar, a shaft mounted on the platform, a gear on the shaft engaging the rack, a motor mounted on the platform adapted to revolubly actuate the shaft, a reversing switch for the motor and means to actuate the switch mounted on the bar and platform in such relation that the switch is actuated after a determinable relative movement of the platform and the bar, a main frame mounted at one end upon the platform and having its other end pivotally mounted on the tube shaft, an auxiliary frame detachably mounted on the main 105 frame and extending adjacent to and being wholly disposed without the leer, a conveyor belt removably mounted on the main and auxiliary frames adapted to carry articles to the leer, a chute carried by the auxiliary frame extending into the leer and adapted to direct articles from the conveyor belt into the leer, a conveyor within the leer, a guide extending between the chute and the leer conveyor, means to actuate the leer conveyor and means controlling the leer conveyor actuating means adapted to intermittently render the leer conveyor actuating 110 means operative, whereby the leer conveyor may be actuated upon the arrival of the frame at its lateral limits of oscillation.
- 25 9. In a device of the class described, a frame oscillating device comprising a bar, a platform, rollers carried by the platform engaging the bar, whereby relative lateral movement of the platform and bar may be attained, a pivotally mounted frame supported by the platform, a reversing motor mounted on the platform, a connection between the motor and the bar whereby relative movement of the bar and platform may be effected, a reversing switch for the motor, an arm controlling the switch, and stops 115 mounted on the bar adapted to be engaged by the arm whereby to actuate the switch.
- 30 10. In a device for automatically controlling a conveyor and a frame adapted to be actuated laterally between the side edges of such conveyor, the combination of a bar, a platform capable of lateral movement over the bar, a frame supported by the platform, a conveyor between the lateral edges of which the frame may be moved, a motor on the platform, a reversing switch on the platform controlling the motor, a connection between the motor and the bar whereby relative movement of the platform and bar may be attained, blocks mounted on the bar, 120
- 35 11. In a device for automatically controlling a conveyor and a frame adapted to be actuated laterally between the side edges of such conveyor, the combination of a bar, a platform capable of lateral movement over the bar, a frame supported by the platform, a conveyor between the lateral edges of which the frame may be moved, a motor on the platform, a reversing switch on the platform controlling the motor, a connection between the motor and the bar whereby relative movement of the platform and bar may be attained, blocks mounted on the bar, 125
- 40 12. In a device for automatically controlling a conveyor and a frame adapted to be actuated laterally between the side edges of such conveyor, the combination of a bar, a platform capable of lateral movement over the bar, a frame supported by the platform, a conveyor between the lateral edges of which the frame may be moved, a motor on the platform, a reversing switch on the platform controlling the motor, a connection between the motor and the bar whereby relative movement of the platform and bar may be attained, blocks mounted on the bar, 130
- 45 13. In a device for automatically controlling a conveyor and a frame adapted to be actuated laterally between the side edges of such conveyor, the combination of a bar, a platform capable of lateral movement over the bar, a frame supported by the platform, a conveyor between the lateral edges of which the frame may be moved, a motor on the platform, a reversing switch on the platform controlling the motor, a connection between the motor and the bar whereby relative movement of the platform and bar may be attained, blocks mounted on the bar, 135
- 50 14. In a device for automatically controlling a conveyor and a frame adapted to be actuated laterally between the side edges of such conveyor, the combination of a bar, a platform capable of lateral movement over the bar, a frame supported by the platform, a conveyor between the lateral edges of which the frame may be moved, a motor on the platform, a reversing switch on the platform controlling the motor, a connection between the motor and the bar whereby relative movement of the platform and bar may be attained, blocks mounted on the bar, 140
- 55 15. In a device for automatically controlling a conveyor and a frame adapted to be actuated laterally between the side edges of such conveyor, the combination of a bar, a platform capable of lateral movement over the bar, a frame supported by the platform, a conveyor between the lateral edges of which the frame may be moved, a motor on the platform, a reversing switch on the platform controlling the motor, a connection between the motor and the bar whereby relative movement of the platform and bar may be attained, blocks mounted on the bar, 145
- 60 16. In a device for automatically controlling a conveyor and a frame adapted to be actuated laterally between the side edges of such conveyor, the combination of a bar, a platform capable of lateral movement over the bar, a frame supported by the platform, a conveyor between the lateral edges of which the frame may be moved, a motor on the platform, a reversing switch on the platform controlling the motor, a connection between the motor and the bar whereby relative movement of the platform and bar may be attained, blocks mounted on the bar, 150
- 65 17. In a device for automatically controlling a conveyor and a frame adapted to be actuated laterally between the side edges of such conveyor, the combination of a bar, a platform capable of lateral movement over the bar, a frame supported by the platform, a conveyor between the lateral edges of which the frame may be moved, a motor on the platform, a reversing switch on the platform controlling the motor, a connection between the motor and the bar whereby relative movement of the platform and bar may be attained, blocks mounted on the bar, 155

an arm adapted to engage the blocks and to actuate the reversing switch upon engagement with the blocks, a normally inoperative motor adapted to actuate the conveyor, cams mounted on the bar, normally spaced contact blocks mounted on the platform adapted to be brought into engagement whereby the second mentioned motor may be rendered operative, and means associated with the contact blocks adapted to engage the cams whereby to bring the contact blocks into engagement one with the other.

11. In a device of the class described the combination of a frame, shafts mounted revolvably at the opposite ends of the frame, a pair of sprocket wheels on each shaft, each of the sprocket wheels on one shaft being aligned with a sprocket wheel on the other shaft, chains extending about the aligned sprocket wheels, each chain comprising a series of axles, a roller mounted on each axle intermediate the ends of the axle, links pivotally joining adjacent axles and being disposed at the opposite ends of the axles, the links carried by each axle being spaced by the rollers, angle brackets mounted pivot-

ally on the axles, the angle brackets carried on one chain, extending toward the angle brackets carried by the other chain, rods connecting each of the angle brackets on one chain with an angle bracket on the second chain, a flexible belt carried by the rods, and tracks carried by the frame adapted to be engaged by the rollers.

12. In a device of the class described the combination of a conveyor for bottles, means to alternately roll the bottles in opposite directions during the carriage thereof.

13. In a device of the class described the combination of sprockets, tracks extending between the sprockets, rollers movable over the tracks between the sprockets, angle brackets carried by the rollers, links connecting the rollers, and an endless belt carried by the angle brackets and disposed in alignment with the axes of the rollers.

In testimony whereof, I have hereunto subscribed my name this 15th day of May, 1922.

PERCY Q. WILLIAMS.
